ABDOMINAL SUPPORT

Gertrude Guenther, Philadelphia, Pa.

Application July 7, 1932. Serial No. 621,167

1 Claim. (Cl. 2—41)

My invention relates to new and useful improvements in abdominal supports, and has for its object to design and form an abdominal support for hospital and like use so as to provide for the ready application of the support without moving the patient from the bed and which when applied to the patient may be drawn as tightly around the portion of the body to be supported as is desired by simply drawing upon slip 5 buckles provided for that purpose.

A further object of the invention is to form the primary supporting member of an independent section of fabric which is connected to the body portion of the device by equalizing straps, 15 which in turn are connected in pairs to the adjusting straps.

A still further object of the invention is to provide a special form of stay for the front edge of the body portion of the device, which stay includes a series of hooks with which the elongated 20 eyes through which the equalizing straps are threaded and intended to slide.

A still further object of my invention is a secondary support or elastic band immediately 25 below the primary support, one end of said band being stitched to one edge of the body portion of the device, while the other end of this band is provided with eyes for engagement with hooks formed by a secondary stay carried by the front 30 edge of the body of the device.

With these and other ends in view, this invention consists in the details of construction and combination of elements hereinafter set forth and then specifically designated by the claim.

In order that those skilled in the art to which 35 this invention appertains may understand how to make and use the same, I will describe its construction in detail, referring by numerals to the accompanying drawing forming a part of 40 this application, in which:—

Fig. 1 is a front view of a garment made in the form of an abdominal support embodying my invention.

Fig. 2 is a detail view of the main stay.

Fig. 3 is an edge view of Fig. 2.

Fig. 4 is an end view of Fig. 2.

Fig. 5 is a section on the line 5—5 of Fig. 1.

In carrying out my invention as herein embodied, 10 represents the body of an abdominal support which is in the general form of a short corset or like garment and 11 are series of tabs or short straps which are stitched to the body adjacent one of the front edges thereof and these tabs carry elongated metal loops 12 for the 55 purpose hereinafter explained.

13 represents a stay formed from a single piece of wire so bent as to produce the hooks 14 and to give to the stay a soft spring flexibility. This stay 13 is secured to the front edge of the body opposite the loops 12, by being stitched between 60 the layers of the fabric of the garment the hooks standing out from the outer surface of the garment as clearly shown in Fig. 5.

15 represents the primary support of the garment for compressing and supporting the 65 abdomen of the person wearing the garment, and this support is an independent piece not being stitched to the body of the garment, one edge thereof having the ends of the equalizing straps 16 stitched thereto as indicated at 17 and these 70 equalizing straps are threaded through the elongated loops 12 and also through the elongated loops 18, the latter being attached to certain of the ends of the adjusting straps 19.

20 represents the detachable equalizing straps, 75 the ends of which are stitched to the opposite edge of the support 15 as indicated at 21 and these equalizing straps are threaded through the elongated eyes 22, which latter are adapted to engage and coact with the hooks 14 after the 80 manner of the ordinary hook and eye. These equalizing straps 20 are also threaded through the elongated loops 23. Each of the adjusting straps are passed through the elongated loops 23 and run backward from said loops and are 85 folded upon themselves, the free ends of the adjusting straps having attached thereto the grip buckles 24.

By the arrangement just described, it will be seen that the abdominal support section 15 may 90 be detached from one of the front edges of the body by disengaging the elongated eyes 22 from the hooks 14 and thus permitting the entire garment to be spread open and flat upon a bed and stretcher in order that the patient may be 95 rolled or otherwise moved on to the body of the garment; and after this has been accomplished, the support 15 is drawn across that portion of the body of the patient which is to be supported, the elongated eyes 22 being re-engaged with the hooks 14 so that by unfastening the grip buckles 24 and drawing them in the direction of the arrow adjacent thereto the front edges of the body of the garment will be drawn toward each other at a ratio approximately 100 three to one to the movement of said buckles, thus multiplying the pull upon the edges of the garment approximately three to one relative to the pull upon the buckles, thus requiring but little exertion on the part of the manipulator to 110
